UNITED STATES PATENT OFFICE.

MADISON J. LORRAINE, OF ST. LOUIS, MISSOURI.

CAR-COUPING.

SPECIFICATION forming part of Letters Patent No. 391,416, dated October 23, 1888.

Application filed February 24, 1888. Serial No. 265,204. (No model.)

To all whom it may concern:

Be it known that I, MADISON J. LORRAINE, of the city of St. Louis, in the State of Missouri, have invented a new and useful Improvement in Car-Couplings, of which the following is a full, clear, and exact description.

My invention relates to that class of car-couplings in which the end of the draw-head is provided with a clutch or hook which is free to turn or swing laterally to a limited extent. In ordinary couplings of this class the clutch or hook is attached to the draw-head by means of a bolt or pivot; and the principal object of the herein-described improvement is to so construct the coupling that this bolt or pivot can be dispensed with, as is hereinafter more fully described.

In the drawings herewith annexed, Figure 1 is a plan view of the upper side of the coupling head or clutch. Fig. 2 is a plan view of the under side of the same. Fig. 3 is a section showing the inside of the lower half of the draw-head. Fig. 4 is a section of the upper half of the same. Fig. 5 is a cross-section along line *x y* of the previous figures, showing the coupling-head attached to the draw-head in the position it would occupy when closed. Fig. 6 is a bottom view of the cap used in this construction, and Fig. 7 is a cross section of the same.

The accompanying drawings show the parts by which the automatic action of the head is obtained, and for which Letters Patent are being asked in an application filed January 21, 35 1888, and numbered, serially, 261,548.

It is not considered necessary to show the locking mechanism, as any desired automatic lock may be used.

Similar letters of reference denote identical 40 parts.

A is the coupling head or clutch, which may be made of any desired shape, whether *D*, *S*, or *V* in form, or as shown by the dotted lines in Figs. 1 and 2. The coupling head or hook 45 may be attached either at its center, its rearward end, or its forward end, at *e*, to the draw-head, as may be desired.

As far as the construction herewith claimed is concerned, the shape of the hook or the location of its attachment to the draw-head in no 50 way interferes with its successful application.

D is the curved slide or slot in which the automatic action of the head depends, and *D'* is the lug on which the slide *D* rides.

E is a boss or protuberance on the upper 55 side of the hub of the coupling-head. This boss can be made plain, but is preferably constructed with the offset shown.

E' is an upraise designed to receive the boss *E* and its attached cap. 60

E'' is a boss rising from the upper side of the lower finger of the draw-head.

E³ is a collar, circular in shape, and open toward the rearward end of the coupling-head.

E⁴ is a loose cap designed to fit on top of the 65 boss *E* after it is in position in the draw-head.

F F' F² are holes designed to receive a pin to retain the coupling-head in a locked position.

R represents the draw-head, and *S S'* are a 70 succession of recesses and teeth designed to interlock the coupling-head with the draw-head when the coupling-head is closed.

It will be noticed that a space exists between the bottom of the coupling-head and the lower 75 finger of the draw-head. This is to allow sufficient room for the entrance of the coupling-head, and, in connection with an automatically-opening head, gives ample play for the head to rise and fall. With couplers not having automatic heads the cap can be dispensed with, and a key passed through the lower boss or a spring-collar be fitted around it to keep the head in a raised position.

As the draw-head is cast in one piece, it is 85 important that a proper knowledge of the way of inserting the coupling-head in the draw-head be had. It is done in the following manner: First, the cap *E⁴* is inserted in the ring *E'* and upheld there, or the draw-head placed 90 in such position that the cap cannot fall. The coupling-head is then turned in the position it would have when open, and with the lower side of the hub resting on the lower finger of the draw-head. The coupling-head then being down, and taking up the vacant space beneath, (shown in Fig. 5,) gives sufficient clearance for the boss *E* to pass under the upper finger of the draw-head. The collar *E³* being cut away in line with the entering movement, 95 100 allows the head to be pushed into position until the boss *E²* fits properly in the collar. The

coupling-head now being in position, the cap E⁴ is allowed to fall and will fit over the top of the boss E. The coupling-head is now still down and cannot be withdrawn the way it entered, because the top of the cap E⁴ comes above the lower face of the upper finger of the draw-head, and it cannot be withdrawn in any other direction, because both the cap E⁴ and the collar E³ serve to retain it.

10 When the coupling-head is closed, by reason of the curved slide D riding up the lug D', the coupling-head is raised into the position shown in Fig. 5. This raising movement of the head is particularly described in a patent granted Lorraine and Aubin, August 30, 1887, numbered 369,195, and in an application for reissue of the same.

When the coupling head is closed, it cannot then be withdrawn, because it is interlocked 20 with the draw-head at S S', Figs. 1 and 4, and because the boss E serves to hold it against the collar formed by the recess E'. Pins inserted in the holes F F' F² may also assist to retain it.

By the construction shown and claimed the 25 coupling is simplified and much strengthened, as the openings for the pivot-pins, which weaken the parts, are dispensed with.

What I claim is—

1. In a car-coupling of the type described,

in which the draw-head is made or cast in one 30 piece, the coupling head or hook A, attachable and secured to the draw-head R by the combination of bosses E and E², the upraise E', and the collar E³, and the means for keeping the coupling-head in a raised position, all 35 substantially as described, for the purposes set forth.

2. A draw-head constructed as described, in combination with an automatically-opening coupling head or hook attached thereto by 40 means of the bosses, collar, and upraised ring, and the auxiliary cap E⁴, all substantially as and for the purposes described.

3. The combination of a coupling-head constructed as described, with the draw-head 45 constructed as described, and the cap E⁴, or a collar to surround the lower boss, for the purpose set forth.

4. In a car-coupling in which the draw-head is made in one piece and having an attached 50 swinging coupling-head, the combination of bosses and collars, substantially as described, for the purposes set forth.

MADISON J. LORRAINE.
